UNITED STATES PATENT OFFICE.

EDWARD I. INGLES, OF INDIANAPOLIS, INDIANA.

APPARATUS FOR PREVENTING INCrustATION OF WATER COILS.

Application filed March 11, 1926. Serial No. 94,020.

This invention appertains to water heaters and the primary object of the invention is the provision of a novel method and means for preventing the adhering of sediment on the inside of a water coil, thereby effectively lengthening the life thereof and the prevention of the gradual closing of the coil through the said adhesion of foreign matter thereto.

It is generally known that the life or period of useful service of water heating devices in common use does not depend materially upon the durability of the material from which they are made, but depends primarily upon and is limited by the time in which minute particles, which separate from the water while the same is being heated, close the device so that the water cannot flow through it. The minute particles when once attached adhere very firmly to the interior of the coil until the walls thereof become thickened by such particles, which finally entirely close the device so that the water cannot flow through it, which results with the coil breaking, sometimes with violent destructive explosions.

The length of time in which a common water heating device will give efficient service ranges from a few months to a few years, depending upon the quantity of water heated, the interior diameter or size of the device and the character of the water used, but in every case the efficiency of the heating device constantly diminishes in proportion as the adhesion attaches to and thickens its walls. The thickening of the walls is commonly called "liming up" and when the adhesions are once attached, there is no practical way of removing the same.

It is therefore a prime object of the invention to provide a novel method of preventing the attaching of such adhesion of any sediment from the water on the walls of the coils, the method including novel means for circulating with the water through the coil for constantly keeping the walls clear from all sediment.

Another object of the invention is the provision of a novel method for preventing the liming up of water coils embodying the use of a non-corrodible ball mounted directly within the coil for continuous circulation through the coil with the water being heated.

A further object of the invention is the provision of novel means for preventing the

adhesion of particles to the inside of a water coil which includes means for reaming out the interior of the coil to insure a smooth bore therethrough and the placing of a non-corrodible ball of a slightly less diameter than the bore of the coil therein for continuous circulation therethrough, means being provided for permitting the dropping of the ball to the lowermost branch of the coil after the same has been moved with the water to the topmost branch of the coil.

A still further object of the invention is to provide a novel method and apparatus for preventing the collection of foreign matter on the inner surfaces of water heaters of the above character, which will be durable and efficient in use, one that will be simple and easy to manufacture and one which can be incorporated with any type of water heater.

With these and other objects in view, the invention consists in the novel construction, arrangement and formation of parts, as will be hereinafter more specifically described, claimed and illustrated in the accompanying drawings, in which drawings:

Figure 1 shows the application of my improved device to a water heater commonly used in stoves and furnaces,

Figure 2 is a plan view of a coil which can be successfully used in such type of water heaters, and

Figure 3 is a diagrammatic view showing the application of my device to water heaters using a source of extraneous heat such as gas, oil, electric heaters.

Referring to the drawings in detail, wherein similar reference characters designate corresponding parts throughout the several views, the letter A generally indicates the fire pot of a conventional furnace or range with a water coil or loop B arranged therein. As usual in such types of heaters a stand boiler of the desired capacity C is arranged adjacent to one side of the furnace or range having extending into the upper end thereof of the source of cold water supply indicated by the reference character 5 which as shown leads into and terminates adjacent to the lower end of the stand boiler. The upper end of the boiler has communicating therewith a pipe 6 for supplying hot water to the various points of use. Communicating with the lower end of the boiler is a pipe 7 for conveying the cold water from the boiler to the coil or loop B. Connected with the hot

water pipe 6 by the use of a suitable T or other joint 8 is the outlet hot water pipe 9 for the coil.

The coil or loop B can be of any preferred character and constructed from any desired material and as shown includes the lower leg 10, an upper leg 11 and the connecting curved portion 12. As shown the legs 10 and 11 have their outer ends threaded, as at 13 and 14 arranged in the same vertical plane, for a purpose, which will be hereinafter more specifically described. Prior to the formation of the coil or loop the desired length of tube is taken and the same is reamed or drifted 15 out so that the inner surface or bore thereof will be smooth without any obstructions therein. The tube is now taken and bent in any preferred way to form the coil or loop. The threaded ends 13 of the legs 10 and 11 20 are connected together by novel fittings 14 and 15. The fittings 14 and 15 can be of the elbow type, and are arranged in the same vertical plane with their adjacent terminals arranged in abutting relation and provided 25 with flanges 16, which are connected together in any preferred way to provide a fluid tight joint. The fitting 14 is provided with a laterally extending tap 17 of a less diameter than the coil or loop B and has attached 30 thereto the cold water pipe 17. A tap 18 is formed on the upper end of the fitting 15 and is of a greater diameter than the tap 17 and has connected therewith the outlet or hot water pipe 9.

35 In accordance with this invention, a ball 19 formed of non-corrodible material is placed directly within the coil or loop B and this ball is preferably of a slightly less diameter than the coil to permit the free 40 movement of the ball therein.

In operation of the improved device the ball 19 will be carried with the water as the same circulates through the coil or loop B and will rise from the leg 10 through the 45 curve 12 to the upper leg 11 into the fitting 15, where the same will fall by its own weight into the fitting 14 and thence again into the leg 10. The ball will travel continuously through the coil or loop and it 50 has been estimated that the same will make five complete cycles a minute. The traveling of the ball through the coils or loop will effectively prevent the adhering of foreign 55 particles on the inner surface of the coil, thereby keeping the same clear of obstructions at all times.

In Figure 3 of the drawings I have shown the novel method of keeping a water heater clear of obstructions applied to a helical water heater of the type generally heated by gas and, as shown, the heating coil D is arranged within a suitable casing E, in which the heating means is arranged. The ends of the coil D project through the casing as 60 shown and can be arranged in the same

vertical plane and have terminals thereof threaded for the reception of fittings 20 and 21 which can be of the elbow type. These fittings have their adjacent ends connected by a suitable pipe or the like 22. The lower elbow 20 has a tap 23 projecting laterally therefrom which is of a less diameter than the coil. This tap has connected thereto the feed pipe 24 for permitting the entrance of cold water into the heater. The fitting 21 has formed thereon a tap 25 to which is connected the hot water pipe 26 which can lead to any desired point. The coil D has its bore made smooth by any desired method and a suitable ball 27 formed of non-corrodible material is placed therein. The ball 27 is made in the same manner as the ball 19 and travels through the coil by the circulation of the water therethrough rising from the lowermost convolution of the coil 25 to the uppermost into the fitting 21, hence it drops by its own weight into the fitting 20 and then again into the lower convolution. By this method the adhesion of all sediment to the inner face of the coil is 30 eliminated.

While in the drawings I have only shown the method applied to two types of heaters, it is to be understood that the same method can be applied to other types and to devices 35 for generating steam of a similar character.

From the foregoing description, it can be seen that I have provided a novel process for preventing the lining up of water heaters and the like.

Changes in details may be made without departing from the spirit or the scope of this invention, but:

What I claim as new is:

1. The combination with a hot water 105 heater including a coil having its outlet and its inlet arranged substantially in the same vertical plane, vertically arranged fittings connected to each other and to the inlet and the outlet, a supply for cold water connected with the lower end of the fittings, and an outlet pipe for the warm water connected with the upper end of the fittings, of a ball 110 arranged in the coil and adapted to travel by the circulation of water therethrough 115 from the lowermost point of the coil to the uppermost part of the coil and return by gravity to the lowermost point of the coil when the same reaches the fittings.

2. The combination with a hot water 120 heater including a coil having its inner surface finished to present a smooth unbroken surface, the inlet and the outlet of the coil being arranged substantially in the same vertical plane, vertically arranged fittings connected to each other and to the inlet and the outlet of the coil, a cold water pipe communicating with the fittings adjacent to the inlet of the coil, a hot water outlet pipe communicating with the fittings adjacent to the 125 130

outlet of the coil, the cold water pipe being of a less diameter than the coil, of a ball formed of non-corrodible material and of a slightly less diameter than the diameter of the coil arranged therein to travel with the circulation of water through the coil from the lowermost point thereof to the uppermost point thereof, the ball being adapted to be returned by gravity to the lowermost point of the coil through the fittings.

3. The combination with a water heating coil having upper and lower legs and a bend connecting the legs at one end, of a curvilinear coupling connecting the other ends of the legs and having oppositely located means for the connection of water inlet and outlet pipes thereto, the coupling being interiorly of greater diameter than the legs, and a substantially spherical cleaning element freely movable in the circuit comprising the legs, the connecting bend, and the

coupling and of a diameter slightly less than the interior diameter of the said legs and bend.

4. The combination with a water heating coil having upper and lower legs and a bend connecting the legs at one end, the other ends of the legs being both located in the same vertical plane, of a curvilinear coupling connecting the last mentioned ends of the legs and vertically disposed and having means at its upper side for the connection of a water outlet pipe and means at its lower side for the connection of a water inlet pipe, the coupling being interiorly of greater diameter than the legs, and a substantially spherical cleaning element freely movable in the circuit comprising the legs, the connecting bend, and the coupling and of a diameter slightly less than the interior diameter of the said legs and bend.

In testimony whereof I affix my signature.
EDWARD I. INGLES.
